UNITED STATES PATENT OFFICE

OVIDE L. MARTIN, OF BRADLEY, ILLINOIS

STORM WINDOW

Application filed August 13, 1928. Serial No. 299,840.

This invention aims to provide a novel means whereby storm sashes may be mounted upon a window frame, and operated.

It is within the province of the disclosure 5 to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes 10 in the precise embodiment of the invention herein disclosed, may be made within the scope of what is claimed, without departing from the spirit of the invention.

In the accompanying drawings:—

Figure 1 shows in front elevation, a device 20 constructed in accordance with the invention;

Figure 2 is a transverse section on the line 2—2 of Figure 1;

Figure 3 is a longitudinal section showing the storm sashes closed;

Figure 4 is a section showing one of the storm sashes closed, and the other of the storm sashes opened.

The device includes a frame, which is a composite structure, the frame including a 30 casing 1 in which a lower sash and an upper sash 3 are slideable the lower sash 2 operating between guide strips 4 and 5 on the stiles of the casing 1, and the upper sash 3 sliding between the guide strips 5, on the one hand, and the stiles of a supplemental frame 6, on the other hand, the frame 6 being secured to the forward portion of the casing 1. The stiles of the supplemental frame 6 have tracks 7.

A facing or finishing frame 8 is secured in 40 place in front of the frame 6 and the stiles of the facing 8 are provided with guides 9.

On the tracks 7, a sash 10 is mounted to slide, the sash 10 carrying a screen 11. On the guides 9, a sash 12 is mounted to slide, the sash 12 carrying a pane 14, preferably made of glass. The top of the sash 12 is connected to the top of the sash 10 by flexible elements 15 trained around pulleys 16 which are morticed into the lintels of the facing 8 and 50 of the supplemental frame 6, the sashes 10

and 12, thus mutually counterpoising each other.

A closure 17 is provided and includes a pane 18, preferably made of glass. The top of the closure 17 is hinged at 19 to the lintel of the facing 8. The closure 17 is adapted to shut tightly against the outer surface of the facing 8, as shown at 20 in Figure 3, and when the sash 12 is lowered, the upper cross rail of the sash 12 overlaps the lower cross rail 60 of the closure 17, as shown at 21, and it will be seen that, thus, a storm window is provided which will keep the elements from finding their way into the building. Links 22 are pivoted at 23 to the bottom rail of the closure 17. The links 22 have outwardly extended fingers 24 which are received detachably in 65 bearings 25 on the outer surface of the sash 12, near to the lower end of the sash.

In practical operation, when the sash 70 10 which carries the screen 11 is pulled down, the flexible elements 15 raise the sash 12 from the position shown in Figure 3, and the storm window closure 17 is swung outwardly to the dotted line position of Figure 3. The operation above described opens the lower part of the window and places the screen 11 in the lower part of the window. In the event that the operator wishes to open the upper part of the window, leaving the lower part of the window closed, the sash 10, with the screen 11, remains raised as in Figure 4 and the sash 12 with the pane 14 remains lowered. The links 22 are resilient enough so that the fingers 24 can be sprung out of the bearings 25, 85 and, then, the closure 17 may be swung outwardly into the position shown in Figure 4, the links 22 resting on the upper cross rail of the sash 12, with the fingers 24 in contact with the guides 9, the links 22, thus, serving 90 as props for maintaining the closure 17 in the partially opened position of Figure 4. When the parts are arranged as last above described, it is obvious that there is ventilation through the upper part of the window, by 95 way of the screen 11.

What is claimed is:

1. In a device of the class described, a frame, an upper closure hinged at its upper end to the frame, a link pivoted to the upper 100

closure, and mechanism for pivotally connecting the link with the lower closure, said mechanism being a separable connection whereby the lower end of the link may be set free, for engagement with the frame, thereby to permit the upper closure to be propped open when the lower closure is down.

2. In a device of the class described, a frame, a lower closure slideable in the frame, an upper closure hinged at its upper end to the upper end of the frame, each of the closures extending approximately one-half the height of the frame, a screen of approximately the same height as the upper closure and slideable in the frame, the screen being of approximately the same height as the lower closure, and means for holding the upper closure open when the lower closure is lowered and the screen is raised.

3. In testimony that I claim the foregoing as my own, I have hereto affixed my signature.

OVIDE L. MARTIN.
